CLAIM

The ornamental design for a camera, as shown and described.

DESCRIPTION

FIG. 1 is a top, front and right side perspective view of a camera showing our new design;

FIG. 2 is a top, front and left side perspective view thereof;

FIG. 3 is a bottom, rear and right side perspective view thereof;

FIG. 4 is a bottom, rear and left side perspective thereof;

FIG. 5 is a front view thereof;

FIG. 6 is a rear view thereof;

FIG. 7 is a right side view thereof;

FIG. 8 is a left side view thereof;

FIG. 9 is a top view thereof; and,

FIG. 10 is a bottom view thereof.

The broken lines depict portions of the camera in which the design is embodied that form no part of the claimed design. Additionally, the broken lines which are shown immediately adjacent to the shaded areas represent the bounds of the claimed design and form no part of the claimed design.

1 Claim, 2 Drawing Sheets
